UNITED STATES PATENT OFFICE.

FRANK F. JACKSON, OF BROOKLYN, NEW YORK, ASSIGNOR TO HAAS BROTHERS FABRICS CORPORATION, OF NEW YORK, N. Y., A CORPORATION OF NEW YORK.

DESIGN FOR A TEXTILE FABRIC.

Application filed March 10, 1923. Serial No. 5,433. Term of patent 3½ years.

To all whom it may concern:

Be it known that I, FRANK F. JACKSON, a citizen of the United States, residing at Brooklyn, in the county of Kings and State of New York, have invented a new, original, and ornamental Design for a Textile Fabric, of which the following is a specification, reference being had to the accompanying drawing, forming part thereof.

The figure is a plan view of a portion of a textile fabric illustrating my new design.

I claim:

The ornamental design for a textile fabric, as shown.

In testimony whereof I have hereunto set my hand and seal in presence of two subscribing witnesses.

FRANK F. JACKSON. [L. S.]

Witnesses:

WALTER E. MANHEIM,
EMIL P. REICHERT.
